WALL SWITCH COVER

John D. Birdsall, 1262 Sunset Plaza Drive,
Los Angeles, Calif. 90069

Filed May 30, 1975, Ser. No. 582,292

Term of patent 14 years

Int. Cl. D13—03

U.S. Cl. D8—183

FIG. 1

FIG. 2

FIG. 1 is a front view of the wall switch cover embodying my new design; and

FIG. 2 is a right side elevational view.

The left side elevational view is the same as the right side elevational view. The rear of the cover is plain.

I claim:

The ornamental design for a wall switch cover, substantially as shown and described.
